DISPLAY FIGURE

Benjamin Lehr, Philadelphia, Pa., assignor of fifty one-hundredths to Helen L. Lehr, Philadelphia, Pa., thirty one-hundredths to Rose Burstein and twenty one-hundredths to Benjamin Horowitz, both of Brooklyn, N. Y.

Application June 27, 1933, Serial No. 677,821

5 Claims. (Cl. 223—18.3)

My invention relates to display figures, that is to say, to the figures which are commonly used for displaying garments and the like, and it relates more particularly to the means for supporting such figures whereby danger of their falling will be reduced to a minimum.

It has been customary to use, in connection with such figures, a metallic base plate to which the figure is detachably secured. Considerable difficulty has been experienced in devising a satisfactory means of attaching the figure to the base plate, particularly when the modern form of display figure is used, the postures of which are more nearly lifelike than those of the older types of figure in which both feet were firmly and squarely implanted on the floor.

Two principal forms of supporting means have heretofore been used, one of which comprised the provision of an exposed rod extending upwardly from the base plate to an intermediate portion of the figure which would be covered by the garment. This, however, was objectionable because of its unsightly appearance, and because it frequently interfered with the proper draping of the garments on the figure.

In a later development, a supporting rod extended upwardly from the base plate and passed through one of the legs of the figure. The principal objection to this form was that each time the dressing of the figure was changed, it was necessary to cut a hole through one shoe, which of course rendered the shoe unsalable, and as the shoes used in dressing these figures are usually of the most expensive kind, this resulted in a considerable loss.

The principal object, therefore, of my present invention is to provide simple and efficient means for supporting display figures which will be unobtrusive in appearance, and in the use of which damage to the shoe which is placed upon the figure will be avoided.

A further object of my invention is to provide such a supporting device in which the parts may be readily adjusted to meet varying conditions, and in which certain of the parts may be made interchangeable for the same purpose.

The nature and characteristic features of my invention will be more readily understood from the following description, taken in connection with the accompanying drawing forming part hereof, in which:

Figure 1 is a perspective view of a display figure, with means embodying the main features of my invention shown in connection therewith;

Fig. 2 is a sectional view illustrating one of the

leg portions of a display figure, the device of my invention being shown in connection therewith;

Fig. 3 is a fragmentary plan view of a portion of the device shown in Fig. 2, the leg portion of the figure being omitted;

Fig. 4 is an elevational view of a modified form of supporting device, the same being shown detached from the base plate;

Fig. 5 is a top or plan view of the device shown in Fig. 4;

Fig. 6 is an elevational view illustrating another modified form of my invention, the same being shown mounted on a portion of the base plate.

Referring to the drawing, 10 is a display figure, having a tubular member 11 extending upwardly through one of the leg portions 12 thereof. The base member 13 is of the customary form, comprising a relatively heavy metallic plate of sufficient extension to prevent the figure from falling over when it is secured thereto.

The base plate 13 is provided with a boss 14 extending upwardly therefrom, and having a vertical aperture 15 adapted to receive the lower end of a standard 16, preferably shaped to conform to the rear of the shoe. The lower end of the standard 16 is secured in its proper adjusted position in the boss 14 by means of a thumb screw 17.

To the upper end of the standard 16 there is secured a foot plate member 18, shaped to conform to the heel and rear sole portions of the foot of the figure. The upper end of the plate member 18 may be secured to the upper end of the standard 16 by means of a bolt 19 and a wing nut 20, as shown in Figs. 2, 3, 4, and 5 of the drawing, or it may be integrally joined thereto at that point as shown in Fig. 6.

An upwardly extending rod 21 has its lower end secured to the sole portion 22 of the foot plate member 18. This rod 21 extends into the tubular member 11 provided in one of the leg portions 12 of the figure.

In Figs. 4 and 5 of the drawing, the sole portion 22 of the foot plate member 18 is made adjustable by providing an auxiliary sole piece 23 which is secured to the main sole piece 22 of that form by a bolt 24 extending through slots 25 in the sole pieces. In this instance the upwardly extending rod 21 is secured to the auxiliary sole piece 23.

In preparing the figure, the rod 21 is first inserted in the receptacle provided by the tubular member 11 in the leg portion 12 of the figure 10. The shoe which is to be used is then placed over the foot portion of the figure, it being noted that
